MAGAZINE FOR NESTED ARTICLES

Carl J. Holinger, Plainfield, N. J., assignor of three-fourths to Joseph D' Ambola and Nicholas D' Ambola, both of Newark, and George W. Kupper, Nutley, N. J.

Application May 20, 1948, Serial No. 28,068

5 Claims. (Cl. 312—43)

1

This invention relates to a magazine for use with a dispenser of nested articles such as drinking cups and adapted to serve individual cups as wanted.

It is an object of the instant invention to increase the number of nested cups that may be served from one cup dispenser at every loading of the cup dispenser.

Another object is to decrease the labor requirements in the servicing of devices for dispensing nested articles.

Still another object is to bring the benefits of the individual drinking cup to a greater number at a lower cost.

Other objects of the instant invention will become apparent in the course of the following specification.

In the accomplishment of these objectives, the magazine comprises a housing the interior of which is divided into a delivery compartment and a storage compartment by a gate pivotally disposed in the top and base members of the housing at the front and biased in the direction of the delivery compartment. Coacting with the gate and in the storage compartment is a platform or stack plate horizontally supported along the inboard edge by the gate when rotated perpendicular to the opposed front member of the housing and along the outboard edge by a bracket attached to the inside surface portion of the end member of the housing forming one surface portion of the storage compartment. When a predetermined number of nested drinking cups are in the delivery compartment, the gate is maintained perpendicular to the opposed front member of the housing. However, when the nested drinking cups have been dispensed below a predetermined level, the gate is free to rotate clockwise into the delivery compartment which releases the inboard end of the platform or stack plate freeing the same to rotate downwardly on the bracket support which movement delivers the nested drinking cups stored thereon into the uppermost of the nested drinking cups still remaining in the delivery compartment substantially re-loading the delivery compartment with the nested drinking cups to be dispensed in the usual manner. Of course, similar storage compartments may be placed radially around the delivery compartment with a pivotally mounted gate separating each storage compartment from the delivery compartment and so constructed and arranged that the nested drinking cups in each storage compartment will be moved into the delivery compartment at different predetermined levels of

2

the nested cups in the delivery compartment. Thus, the utility of the containers or magazines for nested articles such as drinking cups has been greatly increased with substantially less labor requirements for servicing and the benefits of the highly sanitary individual drinking cup brought to a greater number.

The invention will appear more clearly from the following detailed description when taken in connection with the accompanying drawings showing by way of example preferred embodiments of the inventive idea.

In the drawings:

Figure 1 is a front elevational view of the magazine for nested articles with part of the front surface portion removed.

Figure 2 is a sectional view along the line 2—2 of Figure 1.

Figure 3 is a sectional view along the line 3—3 of Figure 1.

Referring now in greater detail to the drawings in which like reference numerals indicate like parts, reference numeral 10 indicates the magazine, and 11 the nested drinking cups.

The magazine 10 is formed from any suitable material with the opposed end members 12 and 13, and the front member 14 in opposed relationship to the back member 15. The top member 16 and the base member 17 complete the housing for the magazine 10. The top of the opposed front member 14 is hingedly supported along one edge by any suitable hinged means 19 and 20 to form the access door 18 which is releasably maintained in the closed position by the latch 21 coacting with the catch 22 to hold the nested cups 11 in place. Below the hinged door 18 is a rectangular opening 23 in the opposed front member 14 and aligned therewith in the back surface portion 15 is a similar rectangular opening 24. In the top member 16 and the base member 17 at the center front and extending toward the left as viewed in Figure 1 are the aligned slots 25 and 26 adapted for the guidance of the later described pivotally mounted gate 27. Through the base member 17, at the right in Figure 1, is a circular opening 28 through which the nested cups 11 pass toward the dispenser (not shown). Around the opening 28 is a downwardly extended collar 29 of such diameter as to fit into the top throat of the cup dispenser and made for the purpose of mounting this magazine on the cup dispenser.

The interior of the magazine 10 is divided into a delivery compartment 33 and a storage compartment 34 by the gate 27 pivotally mounted by the vertical rod 35, the top and base of which

are inserted in the aforementioned slots 25 and 26, respectively, for rotary and linear movement as later shown. To the vertical rod 35 are attached by any suitable means the horizontal members 36, 37, and 38 (Fig. 3). Attached at the other ends of the horizontal members 36, 37, and 38 is the upright member 39, substantially shorter than the vertical rod 35, the lower end of which does not touch the base member 17, and adapted to rotate through approximately 90° in the delivery compartment 33. The gate 27 is biased in the direction of the delivery compartment 33 by the spring member 40 attached at one end to the opposed end member 13 by any suitable means and at the other end to the horizontal member 38 of the gate 27 and sufficiently near the vertical rod 35 so as to permit the nested cups 11 to move downwardly without interruption. Near the bottom of the storage compartment 34 is the substantially flat platform or stack plate 41 supported along the wall 12 by the bracket 42 and having at its opposite edge the projection 45 adapted to be supported by the rod 37 of the pivotally mounted gate 27 when the gate 27 is parallel to the wall 12. Along the front and back edges of the platform 41 are ears 43 and 44 adapted to coact with the aforementioned rectangular openings 23 and 24 in the front member 14 and the back member 15 respectively, to hold the stack plate 41 in the compartment 34 and prevent it from interfering at any time with the nested cups in compartment 33. The projection 45 and its symmetrical opposite projection 46 are adapted to not direct the base of the bottom cup on the stack plate away from the center line between the cups in the storage column 34 and the delivery column 33. When the gate 27 is supporting the platform or stack plate 41 and there are sufficient nested cups in the storage compartment 33 so that the rim of the uppermost nested cup 11 is above the bottom of the upright member 39 the nested cups 11 will prevent the gate 27 from swinging into the delivery compartment 33 and withdrawing the support 37 for the platform 41. However, when the uppermost of the nested cups 11 in the delivery compartment 33 falls below the bottom of the upright member 39, the gate 27, actuated by the spring member 40, will swing through the delivery compartment 33 withdrawing the support 37 from the platform 41 which will then fall downwardly to the dotted position shown in Figure 1 and deliver the bottom unit of the nested cups stored thereon into the uppermost cup of the nested cups still remaining in the delivery compartment 33.

Of course similar storage compartments can be added, each on its own radial line from the delivery compartment 33.

The operation is as follows: With the usual type of cup dispenser (not shown) mounted for use, the downwardly extended collar 29 is inserted in the upper throat of the cup dispenser. A sufficient number of nested drinking cups 11 are inserted in the delivery compartment 33 so that when they come to rest on the cup dispenser the rim of the top cup will be higher than the bottom of the upright member 39. The pivotally mounted gate 27 is slid to the left, as viewed in Figure 1, as far as it can be moved in the slots 25 and 26 and the upright member 39 of the gate 27 rotated toward the center of the magazine 10. As the upright member 39 of the gate 27 approaches the center of the magazine 10, the pivotally mounted vertical rod 35 of the gate 27

may be allowed to slide to the right, as viewed in Figure 1, in the slots 25 and 26 under tension of the spring member 40 as far as it will go. The stack plate 41 is then raised and positioned so that the outboard end rests on the horizontal bracket 42 and with the projection 45 on the inboard end thereof on the horizontal member 37 of the gate 27. Both the delivery compartment 33 and the storage compartment 34 may then be loaded with nested drinking cups 11, the gate 27 preventing the rims of the nested cups 11 in the delivery compartment 33 from interlocking and interfering with the rims of the nested cups 11 in the storage compartment 34 as the nested cups 11 in the delivery compartment move downwardly toward the dispensing device. The door 18 is then closed and latched and the magazine 10 is ready for use. If the magazine 10 is to be reloaded before the nested cups 10 in the storage compartment 34 have been moved into the delivery compartment 33, then it is necessary to refill only the delivery compartment 33.

It is apparent the specific illustrations shown above have been given by way of illustration and not by way of limitation and that the structures above described are subject to wide variations and modifications without departing from the scope or intent of the invention, all of which variations and modifications are to be included within the scope of the present invention.

What is claimed is:

1. A magazine for nested articles comprising a delivery compartment, at least one storage compartment, a platform pivotally disposed in the storage compartment, nested articles in the delivery compartment and on the platform, and means associated with said nested articles to withdraw from the platform a support on the side nearest the delivery compartment when the uppermost member of the nested articles in the delivery compartment reaches a predetermined level, one end of the platform being adapted to fall into a position that will direct the bottom member of the nested articles thereon into the uppermost member in the delivery compartment.

2. A magazine for nested articles in combination with a dispensing device comprising a delivery compartment for the nested articles, at least one storage compartment for the nested articles, nested articles in the delivery compartment and adapted to be dispensed by the dispensing device; the magazine further comprising at least one platform hingedly and slidably disposed in the storage compartment, means separating the delivery and storage compartments, said separating means being adapted to support the inboard edge of the platform when the uppermost of the nested articles is above a predetermined level in the delivery compartment and to release the platform when the uppermost of the nested articles in the delivery compartment has fallen below the predetermined level.

3. A magazine for nested articles in combination with a dispensing device comprising a housing, the housing comprising opposed end members, opposed front and back members, a top member, and a base member, an access door substantially at the top of the front member, means releasably securing the access door, an opening in the base member and adapted for the nested articles to pass therethrough, a downwardly extended collar disposed around the opening and adapted for the attachment of a dispensing device, aligned rectangular openings in the opposed front and back members of the housing substan-

tially below the access door and on the side opposite the downwardly extended collar; the magazine further comprising a gate pivotally mounted in the top and base members of the housing substantially at the front center, the gate comprising at least one pivotally mounted vertical member, at least one upright member, at least one horizontal member disposed between the pivotally mounted vertical member and the upright member, a spring member disposed between the horizontal member and the housing and adapted to maintain the gate under tension against the opposed front member of the housing of the side of the downwardly extended collar, a slot in the top and bottom members of the housing coacting with the pivotal mounting means of the gate and adapted for sliding the gate toward and away from the side of the housing having the downwardly extended collar; the magazine further comprising a stack plate, means pivotally securing the outboard edge of the stack plate to the inside surface portion of the opposed end member of the housing most remote from the downwardly extended collar and substantially at the base comprising a bracket, means attaching the bracket to the said end member, an outwardly and downwardly extended rim on the bracket; the stack plate further comprising at least one ear disposed along the front and back edges and adapted to coact with the aligned rectangular openings in the housing, at least one protuberance on the inboard edge of the stack plate and adapted to coact with the horizontal member of the gate when rotated perpendicular to the opposed front member of the housing but to release the same when rotated under tension of the spring member; the magazine further comprising means attaching the dispensing device to the base of the downwardly extended collar, and nested articles inserted in the downwardly extended collar and on the stack plate.

4. A magazine for nested articles in combination with a dispensing device comprising a housing, the housing comprising opposed end members, opposed front and back members, a top member, and a base member, an access door in the front member substantially at the top; the magazine further comprising at least one gate pivotally mounted in the top and base members and adapted to divide the interior of the housing vertically into a delivery compartment and a storage compartment for the nested articles, a circular opening in the base member of the housing substantially under the center of the delivery compartment, means attaching the dispensing

device under the circular opening, a rectangular opening in the front member substantially below the access door on the side of the storage compartment and an aligned rectangular opening in the opposed back member; the magazine further comprising a stack plate, an ear disposed along the front and back edges of the stack plate and adapted to coact with the aligned rectangular openings, means pivotally securing the 10 outboard end of the stack plate substantially horizontal along the inside surface portion of the end member of the storage compartment, at least one projection disposed on the inboard edge of the stack plate and adapted to coact with the 15 gate in maintaining the stack plate horizontal when the gate is parallel to the opposed end members, and means maintaining the gate under tension in the direction of the delivery compartment.

5. A magazine for nested articles in combination with a dispensing device comprising at least one delivery compartment for the nested articles, at least one storage compartment for the nested articles and adapted to coact with the delivery compartment, nested articles in the delivery compartment and adapted to be dispensed by the dispensing device; the magazine further comprising at least one platform horizontally disposed in the storage compartment and adapted for the support of surplus nested articles, means imparting motion of rotation and translation to the platform and adapted to deliver the surplus nested articles stored thereon into the delivery compartment; the magazine further comprising means separating the delivery and storage compartments, said separating means being adapted to support the inboard edge of the platform in a substantially horizontal position when the uppermost of the nested articles in the delivery compartment is above a predetermined level and to release the platform when the uppermost of the nested articles in the delivery compartment has fallen below the predetermined level.
